UNITED STATES PATENT OFFICE.

MARY V. McANDREWS, OF BROOKLYN, NEW YORK.

VANITY CASE.

Application filed September 22, 1922. Serial No. 589,832.

To all whom it may concern:

Be it known that I, MARY V. McANDREWS, a citizen of the United States, and a resident of the city of New York, borough of Brooklyn, in the county of Kings and State of New York, have invented a new and Improved Vanity Case, of which the following is a full, clear, and exact description.

This invention relates to vanity cases and has for an object to provide a light, compact and easily accessible construction adapted to contain a number of different articles.

Another object of the invention is to provide a vanity case divided into a plurality of sections, each section forming compartments presenting mirrors and cosmetics.

A still further object, more specifically, is to provide a vanity case in which there is provided a mirror at a convenient place for certain groups of articles carried in the respective parts of the case.

In the accompanying drawings—

Figure 1 is a top plan view of the case open and showing the respective parts of said compartments.

Figure 2 is a view similar to Figure 1 but showing different compartments.

Figure 3 is a longitudinal vertical section through a vanity case similar to that shown in Figure 1 with the parts partially open, the same being on a larger scale than that shown in Figure 1.

Figure 4 is a side view of the complete box closed, certain parts being broken away for illustrating the arrangement and construction of the fastening means.

Figure 5 is a side view of a tray embodying certain features of the invention.

Referring to the accompanying drawings by numeral, 1 indicates the bottom section of a vanity case which forms what may be termed the lower compartment and 2 the top or lid which forms what may be termed the upper compartment. A division plate 3 is hinged at 4 to the top and bottom 1 and 2 which are connected by the same hinge. The plate 3 is formed with laterally extending annular flanges 5 and 6, flange 6 having a central extension 7 formed with a raised portion 8 adapted to snap into the pressed out portion 9 in the bottom section 1. This structure acts as a resilient lock for holding the parts normally in assembled position. The flange 5 is provided with a pressed out portion 10 adapted to snap into the pressed out portion 11 in the upstanding annular

flange of the top section 2 as indicated particularly in Figures 3 and 4. The flange 5 in addition acts as a housing or auxiliary compartment for receiving a supply of powder or other cosmetic 12 which is mounted on a suitable plate 13 of metal or other desired material. This plate and supply of cosmetics are held in place by a spring 131 pressing against the edge thereof so that there will be a comparatively tight fit. A suitable powder puff is loosely mounted on the pack 12 and the depth of the cover section 2 is sufficient to take care of these two members and in addition to take care of a mirror 14 held in place by a suitable flange 15 whereby when the case is open as shown in Figure 1, the person using the device may use the powder puff and powder 12 and at the same time use the mirror 14.

When it is desired to use the articles in the compartment or section 1, the dividing structure or plate 13 and associated parts are moved over until the pressed out portion 10 snaps into the pressed out portion 11 and then the parts are open so that they will appear as shown in Figure 2. This will allow the person using the device to look into the mirror 16 held in the flange 6 by a suitable U-shaped supporting ring 17, said ring being soldered or otherwise rigidly connected to the flange 6. Arranged in the lower compartment or bottom section 1 is a tray 18 which tray is provided with depressions or sockets 19 and 20, the depression or socket 19 being preferably annular as shown in Figure 2 so as to receive the pack 21 which consists of a supply of rouge or other desired cosmetic and a supporting back 22 of any desired material, as for instance, cardboard or metal. This pack is held firmly in place by a suitable flat spring 23 whereby the pack normally cannot be displaced but which may be removed at any time. The depression or socket 20 is designed to carry a container 24 containing a lip stick 25. A resilient clip 26 is connected with the tray 18 by a suitable rivet 27 whereby the clip may be raised slightly and rotated whenever desired to remove the container 24.

It is, of course, evident that the container 24 could be eliminated and any other article placed therein, as for instance, a lip stick without the container. The tray 18 is made of such a size as to snugly fit the section 1, which tray in addition to the sockets 19 and 20 is provided with depending sections 28

which are more or less resilient and which press against the side walls of the bottom section 1 and in that manner retain the tray in place. It will be noted that the depending section 28' is longer than the other sections 28 in order to provide a space 29 for receiving the portion 7.

The shape of the case as far as the exterior appearance is concerned may be varied widely without departing from the spirit of the invention. Interiorly the shape also may be changed provided the arrangement and the construction of the respective parts are not materially changed whereby the same results will be secured.

What I claim is:—

1. A vanity case, comprising a casing provided with a bottom section, a top section, a division member, a hinge for hinging both of said sections and division member to-

gether, said division member having oppositely extending annular flanges, one of said flanges having a resilient projection and a pressed out portion, the other of said flanges being formed with a pressed out portion and 25 said top and bottom sections each being provided with a pressed out portion for interlocking with the pressed out portions on the division member whereby the parts are normally held in a closed position.

2. In a vanity case of the character described, a tray formed with a depression for receiving a pack, resilient means for holding said pack in said depression, said tray being formed with a second depression for receiving an article, and a clamping member for clamping said article in said second mentioned depression.

MARY V. McANDREWS.
